SEESAW

Frank C. Castelli, Carroll Park, Pa., assignor to
F. C. Castelli Company, Philadelphia, Pa., a
corporation of Pennsylvania

Application February 25, 1948, Serial No. 144,729

Term of patent 7 years

(Cl. D34—5)

To all whom it may concern:

Be it known that I, Frank C. Castelli, a citizen of the United States, residing at Carroll Park, in the county of Delaware and State of Pennsylvania, have invented a new, original, and ornamental Design for a Seesaw, of which the following is a specification, reference being had to the accompanying drawings, forming a part thereof.

In the drawings, Fig. 1 is a perspective view of the seesaw, showing my new design; Fig. 2 is a side elevational view of the seesaw; Fig. 3 is an end elevational view of the seesaw; Fig. 4 is an enlarged fragmentary perspective view of a part of the frame looking in the direction of the arrows 4—4.

I claim:

The ornamental design for a seesaw, as shown and described.

FRANK C. CASTELLI.
